UNITED STATES PATENT OFFICE

ARTHUR FRISCH, OF BROOKLYN, NEW YORK

DOLL-HEAD AND THE LIKE

Application filed April 18, 1929. Serial No. 356,008.

My invention relates in general to dolls, the invention being more particularly related to a movable feature in doll-heads, although the invention is not necessarily confined thereto, but is capable of use in connection with any toy-figure provided with a mouth opening.

The invention has for its main object and purpose the provision of a movable tongue and of movable teeth mounted for operation in association with the mouth opening in the doll-head.

Another object of the invention is the provision of a movable feature of the character referred to, which will be automatic in its operation, being arranged to assume first one position and then another according to the position given to the doll-head.

A still further object of the invention is the provision of a movable feature of the foregoing character which is simple in construction and arrangement, compact, efficient, and inexpensive to manufacture, as well as designed to be interesting and entertaining to children.

Other objects and advantages of the invention will appear hereinafter.

The invention resides in the construction and in the arrangement or arrangements of parts hereinafter described and claimed.

The invention will be best understood by referring to the accompanying drawings, forming a material part of this application, and in which:

35 Figure 1 represents a fragmentary vertical section through a doll-head provided with the movable tongue and teeth features of my invention, the doll-head being here shown in upright position;

40 Fig. 2 represents a similar view showing the doll-head in inclined position;

Fig. 3 represents a front elevational view on a larger scale of the part comprising the support and upper set of teeth;

45 Fig. 4 represents a plan view of the tongue; and

Fig. 5 represents a front elevational view of the swingable part with the lower set of teeth.

50 Referring with more particularity to the

parts illustrated by way of example in the accompanying drawings, 10 designates in general the front or face portion of a hollow doll-head which may be produced in any known or approved manner. Included in 55 the front or face portion are the usual features comprising a nose 11, a chin 12, and lips 13 and 14 which are shown as open or parted to provide a mouth opening 15 through which the movable tongue and teeth features of 60 my invention may be seen.

My invention, in its preferred form of construction as illustrated in the accompanying drawings, comprises a supporting element which is designated in its entirety by the 65 numeral 16 and is represented as composed of a lower front part 17, a rearwardly extending part 18, an upwardly extending part 19, and a forwardly extending part 20.

At the angular junction of the parts 17 70 and 18, there is preferably formed a suitable forward deformation 21 adapted to seat in a concavity 22 provided in the inner face of the lower lip 14, whereby the supporting element may be properly positioned within the hollow head in relation to the mouth opening. At its front end the forwardly projecting part 20 is provided with a depending section or flange 23 arranged to extend alongside the inner face of the upper lip 13 and which is formed or painted in simulation of an upper set of teeth as best illustrated in Fig. 3. The supporting element and the section or flange 23 are so made and proportioned that when the former is secured in position within the doll-head the latter or an appropriate portion thereof will be exposed to view in the mouth-opening 15 immediately below the upper lip 13.

90 The lower front part 17 of the supporting element is represented as being provided with struck out prongs 24 adapted to be pressed into the material of the doll-head so as to secure the supporting element rigidly 95 therewith. In place of the prongs 24, any other equivalent or suitable means of attachment may be employed. Moreover, if desired, the supporting element may be secured in place by means of glue, cement, or 100

other adhesive substance suitable for the purpose.

According to an important feature of my invention, I make use of an angular swingable element 25 which is mounted through a suitable opening 26 provided in the upwardly extending part 19 closely adjacent the rearwardly extending part 18, so that the arm 27 of the swingable element can rest upon the top surface of the rearwardly extending part 18 when the doll-head is in upright or approximately upright position, as illustrated in Fig. 1. At its forward end, the arm 27 is formed or provided with a section or flange 28 in simulation of a lower set of teeth complementary to the upper set of teeth. Preferably and as shown, the section 28 is so made and proportioned with respect to the lower lip 14 that when the doll-head is in upright position as shown in Fig. 1, said section or flange 28 will be concealed by the lower lip. Applied to the lower end of the other arm 29 is a weight 30 which serves as means by which automatically to move the swingable element when the doll-head is inclined from upright position.

According to a further feature of my invention, I provide a tongue member 31 having an enlarged front portion 32. This tongue member is passed through a suitable slot 33 in the upwardly extending part 19 and has a slot 34 through which is passed the end of an arm 35 preferably struck out of the arm 29 of the swingable element. In this manner I prefer to mount the tongue on the supporting element and to pivotally connect it with the swingable element, so that when the doll-head is in upright position with the section 28 concealed behind lower lip 14, the enlarged portion 32 of the tongue will occupy a position between the complementary sections 28 and 23. As shown in Fig. 2, when the doll-head is given a forward inclination, the swingable element will withdraw the tongue so that the section 28 can abut the section 23. By this arrangement, therefore, to project the tongue and conceal the section 28 the doll-head is moved into upright position, whereas in order to retract the tongue and cause the lower section to close against the upper section the doll-head is given a forward inclination. Through this arrangement, I produce the effect of two opening and closing sets of teeth and of a movable tongue which is projected outwardly between the two sets of teeth by reason of the opening movement and which is retracted and concealed when the closing movement has been accomplished.

My invention is characterized by the fact that it is extremely simple, comprising essentially three main parts consisting of a supporting element, a swingable element, and a tongue member. My invention is further characterized by being compact, so that the

parts in their entirety can be readily entered through the usual neck opening (not shown) leading to the interior of the hollow head. Owing to their form and arrangement, the parts, after being entered through the neck opening, can be readily secured in place so that the sections 28 and 23 and as well the tongue member will come in proper relation to the mouth-opening. The parts comprising my invention may be produced from suitable paper, carboard, light sheet metal, or any other appropriate material. The teeth and tongue features may, if desired, be produced by painting or other embellishment.

While I have thus illustrated and described a single preferred form of my invention, it will be understood that changes and alterations in the details of construction as well as in the mode of imparting movement to the swingable element may be made, to which changes and alterations I am entitled, provided the same are effected within the scope of the annexed claims.

I claim:

1. In combination with a head for toy figures having a mouth opening, upper and lower teeth at the inner side of the mouth opening, a tongue member, means supporting the tongue member and the teeth at one side of the mouth opening for relative movement, and a common means operable by tilting the head from an upright position for relatively moving said movable teeth and the tongue member.

2. In combination with a head for toy figures having a mouth opening, upper and lower sets of teeth at the inner side of the mouth opening, one set of teeth being movable towards and from the other set, a tongue member movable between the upper and lower sets of teeth, and a single means operatively connected with said tongue member and the movable set of teeth and operable to move the same relative to each other by tilting of the head from an upright position.

3. In combination with a head for toy figures having a mouth opening, upper and lower sets of teeth at the inner side of the mouth opening, one set of teeth being movable towards and from the other set, a tongue member movable between the upper and lower sets of teeth, means supporting said movable set of teeth and tongue member for relative movement, and a weight member operatively connected with the tongue member and the movable set of teeth operating by gravity upon tilting the head from an upright position to simultaneously move the tongue member and the teeth relative to each other.

4. In combination with a head for toy figures having a mouth opening, a support fixed to the head wall at the inner side of the mouth opening, an upper set of teeth fixed relative to the support, a lower set of teeth mov-

- able on the support towards and from the upper set of teeth, a tongue member movable on the support between said upper and lower sets of teeth, and a common actuating means 5 for said lower set of teeth and the tongue member operatively connected therewith to simultaneously move the same in angularly related paths relative to the upper set of teeth.
- 10 5. In combination with a head for toy figures having a mouth opening, a support fixed to the head wall at the inner side of the mouth opening, an upper set of teeth fixed relative to the support, a lower set of teeth 15 movable on the support towards and from the upper set of teeth, a tongue member movable on the support between said upper and lower sets of teeth, and a weight member operatively connected with one end of the 20 tongue member and with said movable set of teeth operating by gravity to simultaneously move said teeth and the tongue member in angularly related paths upon tilting movement of the head from an upright position.
- 25 6. A teeth and tongue set for toy figure heads comprising a support having a part attachable to a wall of the head adjacent the mouth opening therein, an upper fixed set of teeth on the support, a lower set of teeth 30 mounted on the support for movement towards and from the upper set of teeth, a tongue member movable on the support between said upper and lower sets of teeth, and a single operating member operatively connected with the lower set of teeth and said tongue member to simultaneously move the 35 same along angularly related paths.
7. A teeth and tongue set for toy figure heads comprising a support having a part attachable to a wall of the head adjacent the mouth opening therein, an upper fixed set of teeth on the support, a lower set of teeth 40 mounted on the support for movement towards and from the upper set of teeth, a tongue member movable on the support between said upper and lower sets of teeth, and a weight member connected with said movable set of teeth and the tongue member operable by gravity to simultaneously move 45 said teeth and the tongue member along angularly related paths.
8. A teeth and tongue set for toy figure heads comprising a support having means at one end attachable to the head wall adjacent the mouth opening therein, a fixed set 50 of teeth on said support, a second set of teeth, gravity controlled means on the support connected with the latter teeth to move the same towards and from the fixed set of teeth, and a movable tongue member on the support 55 operatively connected with said gravity controlled means and movable thereby relative to the fixed and movable sets of teeth.
9. A teeth and tongue set for toy figure 60 heads comprising a support having means
- at one end attachable to the head wall adjacent the mouth opening therein, a fixed set of teeth on said support, a second set of teeth, gravity controlled means on the support connected with the latter teeth to move the same 70 towards and from the fixed set of teeth, a tongue member movably mounted at one of its ends upon the support, and an operative connection between said end of the tongue member and the gravity controlled means to 75 actuate said member and project or retract the other end thereof relative to the opposed sets of teeth as said second named set of teeth are moved towards or from the fixed teeth.
10. A supporting member, and means for rigidly securing said member to the inner side of a wall of a doll head with spaced parts of said member disposed above and below a mouth opening in the head wall, and upper and lower sets of teeth carried by said spaced 80 parts of the supporting member.
11. A supporting member having means integrally formed therewith to impale the wall structure of a doll head and secure said member in fixed relation to the wall at the rear 85 side of a mouth opening therein, and upper and lower sets of teeth carried by said supporting member and positioned by the attachment of said member, in proper relation to the upper and lower edges respectively of 90 the mouth opening.
- In testimony that I claim the foregoing as my invention, I have signed my name hereto.
